United States Patent

Des. 241,577
Patented Sept. 21, 1976

241,577

PHOTOGRAPHIC ENLARGER

Wilmot Pramstraller, Brixen, Italy, assignor to Durst AG.
Fabrik Fototechnischer Apparate Bozen

Filed Mar. 12, 1975, Ser. No. 557,828

Claims priority, application Italy Sept. 13, 1974

Term of patent 14 years

Int. Cl. D16—05

U.S. CL. D16—25

Fig. 5.

Fig. 1.

Fig. 2.

Fig. 6.

Fig. 4.

Fig. 3.

Fig. 7.

FIG. 1 is a front elevational view of a photographic enlarger showing my new design;

FIG. 2 is a left side elevational view thereof;

FIG. 3 is a right side elevational view thereof;

FIG. 4 is a rear elevational view thereof;

FIG. 5 is a top plan view thereof;

FIG. 6 is a bottom plan cross-sectional view taken through FIG. 3 along the lines 6—6; and

FIG. 7 is a bottom plan view of the embodiment shown in FIGS. 1-6.

I claim:

The ornamental design for a photographic enlarger, as shown.
